UNITED STATES PATENT OFFICE.

HORATIO THOMAS, OF CHICAGO, ILLINOIS, ASSIGNOR TO THE BOSTEDO PACKAGE AND CASH CARRIER COMPANY, OF ATLANTIC, IOWA.

CASH-CAR ARRESTER.

SPECIFICATION forming part of Letters Patent No. 379,085, dated March 6, 1888.

Application filed October 8, 1887. Serial No. 251,829. (No model.)

To all whom it may concern:

Be it known that I, HORATIO THOMAS, of Chicago, in the county of Cook and State of Illinois, have invented certain new and useful 5 Improvements in Car-Arresters for Cash and Package Carrying Systems; and I do hereby declare the following to be a full, clear, and exact description of the invention, such as will enable others skilled in the art to which it applies 10 pertains to make and use the same.

My invention relates to an improvement in car-arresters for cash and package carrying apparatus, the object of my present invention being to provide a simple and efficient car- 15 arrester which is particularly adapted to suit the construction of the two-track cash and package apparatus that are the inventions of Louis G. Bostedo, filed August 2, 1886, Serial No. 209,781, now Patent No. 369,628, dated September 6, 1887, and Horatio Thomas, filed 20 August 27, 1886, Serial No. 212,010, now Patent No. 368,029, dated August 9, 1887, to render the operation of arresting cars at a station more reliable and afford a more compact device 25 with fewer working parts than have been heretofore employed on two-track systems of the type above mentioned.

With these objects in view my invention consists in certain features of construction and 30 combinations of parts, that will be hereinafter shown, and pointed out in the claims.

In the two-track apparatus for cash and package transportation just referred to, one track is placed immediately above the other 35 in the same vertical plane. Stations for clerks to transmit cash and goods from such points to the cashier's desk or a bundle-table are provided along these main lines. Openings are made in the tracks at stations, and an elevator 40 is furnished at each station to afford a means for the expeditious raising of the car, with a package receptacle attached, from the counter to the upper track, which is preferably made a dispatching-track, while the lower track is 45 the return-way for bundled goods or cash change to be sent from a distant point to any station on the line.

One of the important portions of such an apparatus consists in a device to arrest a car 50 at its proper station and hold it securely upon the elevator of such a station while the car and attached package-receptacle are lowered

to the hand of the clerk or other operator. It is important that this car-arresting device should also embody a means for release of the 55 car when it is raised to the upper track at a station to dispatch it toward the cashier's desk or bundle-table, this release being made simultaneous with the propelling action of another portion of the arrester, that stores the momentum of a car that has been previously arrested at the station on the lower track and discharges the stored energy to give a progressive impetus to a car leaving a station, as just indicated. 65

The car-arrester which is the subject of my present invention will perfectly accomplish the work it is designed to perform, and is specially adapted to locations where abrupt curves are required in the tracks to suit peculiarities 70 of the situation.

I will now describe my invention, reference being made to the drawings, in which—

Figure 1 is a side elevation of a two-track cash and package transporting apparatus at a 75 station, showing the relative position of the track-section bar of the elevator upon which the car-arrester is located. Fig. 2 shows the front side of the track-section bar at a station, with the improved arrester in position thereon. 80 Fig. 3 is also a front side view of the track-section bar of an elevator at a station, the car-arrester being shown in a different position. Fig. 4 is a cross-section of the track-section bar on line xx , Fig. 1, with a car in position on this bar 85 to show the locking-bar of the car-arrester in locked engagement with a stud that projects from the side of the car-frame. Fig. 5 is a side view of the car without its pendent package-receptacle. Fig. 6 is a view of the arrester 90 modified in form to suit the last or end station on a track-line.

Reference to Fig. 1 will show the construction of the car-elevator A. It is made to slide between the parallel vertical standards 95 A' when the cord E is pulled. It is apparent that the elevator may by this means be brought into a position to cause its track-section bar B to line with the lower tracks, C, or upper tracks, D. The track-section bar B is affixed securely to the projecting arms a of the elevator-frame, so as to allow it to align with or lie in the same vertical plane as the main tracks C and D, and therefore to properly fill a gap 100

that may be made between the track ends of either the upper or lower tracks when the top edges of the bar are level with similar edges of either of the track-lines.

5 A removable bar, B', occupies the place of the track-section bar B, to render the track continuous when the elevator is not in aligned position therewith. This movable bar B' is elevated by contact with projections b, formed 10 on the elevator-frame in such relative position as to lift the bar B' when the elevator-frame A is raised to pass this bar. A removable bar, F, spans the gap in the upper track, D, this bar being hinged at the rear edge of 15 the well-hole frame F'. A chain, s, or other flexible connection is attached by one end to the bar F or one of its supporting-arms s', by which it is pivotally attached to the well-hole frame F'. The other end of the chain s is attached to a wing, s², which is placed upon one 20 of the vertical standards A' and made to fit it loosely. The length of the chain s is so proportioned that the contact of the sliding upper portion of the elevator-frame A with the attached ring s² will stretch the chain and elevate the hinged bar F, to permit the elevator 25 track-section bar B to line with the upper track when a car is to be dispatched from a station to the cashier's stand or the bundle-table, as will be hereinafter explained.

The front face of the track-section bar B is recessed to form a cavity for the reception of the arresting and locking mechanism, which will now be explained. A flat bar, G, is made 30 of proper thickness to lie in the recess of the track-section bar B and have its outer face about level with the flanges g h, that remain on the bar, the lower flange, h, affording a supporting-base upon which the bar G may 35 slide, which I designate as the "floor-face" of the bar G. The rear end of the bar G has an integral extension, c, formed into a round rod, that gives support to a spiral spring, c', which bears against the vertical shoulder c² of 40 the bar G, as well as the perforated ear c³, that holds the outer end of the rod c loosely, to permit said rod to slide in this perforated ear, so that the spiral spring will be compressed if the bar G is moved toward the ear c³. At the opposite end of the bar G the 45 width is reduced from the shoulder i to the termination i' of the bar, and the upper edge is cut to produce ratchet-teeth k, which slope rearwardly to adapt them to engage the tripping-lever I, which is pivoted at f and furnished with the spring m. The latter, by its 50 contact with the upper flange, g, of the track-section bar B, will force the inner end of the tripping-bar I to bear upon the serrated edge of the portion G' and lock with these teeth, so 55 that a sliding movement of the bar G toward the ear c³ will compress the spring c' and retain the spring in such a compressed condition.

Upon the exposed face of the ratchet-bar G, just described, a flat locking-bar, H, is pivoted at d. This bar H is curved or bent edge-wise to cause its ends to drop slightly, and at

the forward end a fork or crotch, d', is produced, which is designed to engage a projecting pin affixed to the side of a car, as shown in Fig. 4. On the opposite end of the locking-bar H a pin, e, is affixed to project inwardly. The length of this pin is about equal to the thickness of the bar G, to permit it to enter the notch e' made in this bar G immediately above 75 the pin e. The flange h—that is, the floor on which the ratchet-bar G slides—is cut away between the points n n' to allow the pin e to rise into the notch e', and it is important that the removed portion of the flange h should be 80 so relatively located that the rear end, H', of the locking-bar H may be elevated when the spiral spring c' is uncompressed, as shown in Fig. 1.

The rear end, H', of the locking-bar H is 85 further provided with a depending lug having its forward edge cut to slope rearwardly and round off at the lowest point, e², the pin e, previously mentioned, being attached to the inner side of the lug. The weight of the rear end 90 of the locking-bar H, considered from its point of pivotal attachment to the ratchet-bar G, is in excess of the weight of its forward end, to cause this latter-named portion of the bar to be normally held with its forked ends in line 95 with or slightly above the lower flange, h, of the track-section bar B, the rear end assuming the position shown in Fig. 1.

The transporting-car J (see Fig. 5) has its frame J' constructed with guard-pieces o, that 100 extend a slight clearing distance below the lower edge of the main tracks C D when the car is in motion, to retain it in rolling contact therewith and prevent derailment.

In operation the guard ends o of the frame 105 of the car will be in alignment with the locking-bar H, so that the depending rear end, H', of this bar will collide with the guard end o that is adjacent to it, and this contact of parts will elevate the rear end of the locking-bar H, 110 causing the front forked end, d', to be depressed; and as it is understood that this contact will take place when the parts are in 115 normal position, as shown in Fig. 1, with the spring c' uncompressed, it is evident that when the crotched end d' is depressed to engage a 120 projecting pin, p, of the car J (which will occur when a car runs onto the elevator that is aligned with a lower track) the spring c' will be compressed and held in this condition, and the rearward movement of the ratchet-bar G thus caused will carry the elevated pin e over the flange h or floor of the bar B, thus locking the crotched end d' of bar H in close contact with the engaged pin p, holding it secure as 125 long as the spring c' is compressed. Other devices not necessary to describe in this connection are attached to the opposite side of the track-section bar B, which operate to detach this bar from its supports and allow the elevator, with a locked car, to be properly lowered to the counter. Now, when the car is to 130 be used to dispatch packages or cash to a cashier's stand or bundle-table, the car on the

elevator is raised to the upper track, D, and when the top edge of the track-section bar B is about in a line with top edge of the upper track the free end I' of the tripping-lever I will be depressed sufficiently to release contact of its opposite end with the ratchet-teeth of the bar G, and thus disengage the latter-named piece from its locked adjustment. The liberated bar G will be forced forward by the compressed spring e' and give a starting impetus to the car toward its point of destination, the peculiar form of the crooked end d' of the locking-bar H affording an instantaneous release of the car by its frictionless release of the pin p. The parts will then assume the position shown in Fig. 2, the locked engagement of the car being shown in Fig. 3.

It should be explained that the relative position of the projecting pins p, that are affixed to cars belonging to the several stations on a track-line, must be arranged to suit the construction of the locking-bars of different stations and length of the depending lugs on the rear ends of these bars, so that each car will be arrested at its own station and will freely pass all other stations on the line.

In Fig. 6 is shown a modified form of the car-arrester that is preferably used to arrest a car at the last station on the line, or the station farthest removed from the cashier's desk or bundle-table.

The car for the end station does not require any stop-pin p on its car-frame, as the front end of guard-piece o of the car-frame may be utilized for an abutment-piece, whereby the car may be arrested and held locked.

The simple device shown in Fig. 6 is designed to engage the guard-piece, as will be shown.

A fixed contact-plate, L, is rigidly secured to the side of the ratchet-bar G. The guard-piece o collides with the edge r of this plate, and in this manner arrests the car, the recoil-spring e' absorbing the momentum of the car and neutralizing the shock of such a contact.

In order to lock the car in place, the forward end of the locking-bar H' (see Fig. 6) is pivoted at q on the bar G and has the terminal edge of its rear end cut on an incline to the perpendicular edge of the plate L.

The lower edge of the ratchet-bar G is notched at a point and in a form to correspond with the inwardly-projected lug e², which is affixed to the inner surface of the locking-bar H'. The lug e² is formed with sides sloping toward a flattened narrow apex, t, and, as before intimated, the conformation of the lug e² and the receiving-notch e' are of exactly similar form, to permit the lug to register with the notch when the locking-bar H' is raised from its normal position.

The point of lowest depression of the locking-bar H' is limited by its impinging contact with the stop-pin v, its lower edge resting on this pin when it is allowed to hang free and assume this position by gravity of its body.

The length of the bar H' and its pivoted position is such as to leave a sufficient space be-

tween the edge r of the plate L and the inclined edge s of the free end of the latch-bar that is adjacent to it to afford room to receive between these edges the guard strip or piece of the car-frame to lock the car to the bar B.

It should be explained that in the form of construction just described the lower flanged edge of the track-section bar B is cut away to allow the free action of the locking-bar H' at a point on this bar that will be opposite the free end of the locking-bar H' when the spiral spring e' is uncompressed.

In operation the guard-piece o of the car-frame will slide under the locking-bar H', having contact with the lower edge of this bar when a car runs upon the elevator at a station. This will raise the locking-bar, as it is free to move upwardly when the spring e' is not compressed. As soon as the car strikes the plate L the locking-bar H' will drop into place, and as the recoil spring e' is compressed the ratchet bar, with its attached plate L and locking-bar H', will move rearwardly. This movement will carry the upper flattened edge, t, of the lug e² beneath the flange h of the track-section bar B, and thus lock the car in position securely until the car is raised to the upper track to permit it to be dispatched. When this takes place, the release of the spring e' will return the parts to normal position and the device adjusted to return to the lower track and receive its car when returned from the other end of the line.

Many slight changes might be made in the details of construction of the car-arresting device herein shown and described without departure from its spirit or exceeding its scope—as, for instance, the forked end d' of the locking-bar U might be reversed in position or formed at the opposite end of the bar; or the latch-hook used in form of construction of the ratchet-bar, as devised and shown in the patented cash and package carriers of Bostedo and Thomas, previously alluded to in this specification, might be employed to act in conjunction with the locking-bar and hold the car securely. In the latter case the end d' of the locking-bar H will be made to afford a square abutment in place of the forked end, as shown in Figs. 2 and 3 of the drawings.

I do not therefore wish to limit myself to the exact forms herein shown of my car arresting and dispatching device, but desire a reasonable latitude to vary within the scope of my invention; and,

Having fully described my invention, what I claim as new, and desire to secure by Letters Patent, is—

1. The combination, with a track-section bar carrying a ratchet-bar, a spiral spring, and a tripping-lever for engaging the ratchet-bar and holding the spiral spring compressed, of a locking-bar pivoted to the ratchet-bar and adapted to engage with one end a pin on a car and with the other end to engage the surface of the track-section bar to lock the car in position, substantially as set forth.

2. The combination, with an elevator carrying a track-section, the latter having a notched under side, of a ratchet-bar, a spiral spring to arrest recoil, a tripping-lever, and a vibrating locking-bar having a pin adapted to be moved up into the notch and engage a flange on the track-section bar for holding the locking-bar elevated, substantially as set forth.
3. The combination, with a track-section bar and its ratchet-bar, of a pivoted locking-bar that has a crotched end and a lug or pin projecting from its other end and adapted to lock the crotched end fast to a pin on the car, substantially as set forth.
4. The combination, with a car that has a projecting pin on its frame, of the track-section bar of an elevator, a ratchet-bar on this track-section bar, and a locking-bar pivoted on the track-section bar, forked to straddle the projecting pin on the car-frame and be held in locked contact by the engagement of its

other end with the surface of the track-section bar, substantially as set forth.

5. The combination, with a track-section bar that may be held in alignment with the upper and lower tracks of a two-track apparatus, of a toothed and spring-actuated ratchet-bar, a tripping-lever, a latch-bar pivoted at one end, and an abutment-plate secured to the ratchet-bar, the swinging end of the latch-bar being adapted to hold the guard-piece of the frame of a car between it and the adjacent edge of the depending abutment-plate, substantially as set forth.

In testimony whereof I have signed this specification in the presence of two subscribing witnesses.

HORATIO THOMAS.
